Primary Examiner — Susan Bennett Hattan*Assistant Examiner* — Brett Miller(74) *Attorney, Agent, or Firm* — Allen, Dyer, Doppelt + Gilchrist, P.A. Attorneys at Law(57) **CLAIM**

The ornamental design for a solid fuel cooking device, as shown and described.

DESCRIPTION

FIG. 1 is a environmental perspective view thereof in a solid-fuel cooker;

FIG. 2 is a multi-side perspective view thereof;

FIG. 3 is a multi-side perspective view thereof with the cover thereof removed;

FIG. 4 is a front side view thereof;

FIG. 5 is a top view thereof; and,

FIG. 6 is a bottom view thereof.

The broken lines are included for the purpose of illustrating unclaimed portions of the solid fuel cooking device as well as unclaimed environmental structure. The broken lines in the drawings form no part of the claimed design.
